UNITED STATES PATENT OFFICE.

ROBERT M. WAKEFIELD, OF MOUNT UNION, PENNSYLVANIA.

LAP-LINK.

SPECIFICATION forming part of Letters Patent No. 747,103, dated December 15, 1903.

Application filed July 9, 1903. Serial No. 164,847. (No model.)

To all whom it may concern:

Be it known that I, ROBERT M. WAKEFIELD, a citizen of the United States, residing at Mount Union, in the county of Huntingdon and State of Pennsylvania, have invented new and useful Improvements in Lap-Links, of which the following is a specification.

This invention relates to lap-links; and the primary object of the same is to provide a simple and effective device of this class having coöperating elements precisely similar in contour with openings in the side members in different positions, so that when the elements are turned to accurately coincide to form a complete link the chain-link or other device in engagement with the coinciding elements will be prevented from slipping out of engagement or becoming accidentally detached from the lap-link, and, furthermore, the strain or draft on the parts of the lap-link will be so applied and distributed as to maintain the elements thereof in closed relation.

The invention consists in the construction and arrangement of the several parts, which will be more fully hereinafter described and claimed.

In the drawings, Figure 1 is a side elevation of a lap-link embodying the features of the invention and shown closed. Fig. 2 is a top plan view thereof looking toward the upper edge. Fig. 3 is an elevation of the improved link shown open.

Similar numerals of reference are employed to indicate corresponding parts in the several views.

The numerals 1 and 2 designate the elements of two flat links constituting the main features of the improved lap link or ring, said flat links being of similar size and shape and having their flat faces held in close contact. The element 1 has a downwardly and outwardly inclined slot 3 cut through one of its side members, and the element 2 also has a downwardly and outwardly inclined slot 4 cut through its contiguous side member, the slots 3 and 4 inclining in reverse directions toward the opposite ends of the complete device. The said slots 3 and 4 are located to

one side of the center of each member in which they are formed, and the free ends 50 constructed by the formation of the said slots are pivotally attached by a rivet or other analogous device 5. In other words, the overlapping ends of the elements between the slots 3 and 4 are movably secured to each 55 other, so that when the elements 1 and 2 are disposed as shown by Fig. 3 or so that the element 1 will stand across the element 2 in a plane at right angles to the latter both slots 3 and 4 will be open, and the inclination of the slots as set forth will cause that formed in the element 1 to pass downwardly in coincidence with that formed by the element 2 during the operation of inserting a device to be connected by the lap-link. 65

It will be seen that the present improved form of lap-link is simple in its construction, and slots other than those set forth are unnecessary, as in construction of this class of devices wherein one element or member slips 70 over the other, and, furthermore, the operation of constructing the improved lap-link is materially simplified.

In the operation of connecting an ordinary chain-link or other device to the lap-link the 75 elements 1 and 2 are arranged as shown by Fig. 3, and the chain-link or other device is then inserted through the slot 4 of the element 2 and held adjacent to the end of said latter element near the slot 4. The element 80 1 is then turned over until the slot 3 thereof passes the slot 4 in the element 2, when the chain-link in the latter element is then pushed through the slot 3. The chain-link or other device will then be in engagement 85 with both elements, and the element 1 is turned farther until it assumes the position in relation to the element 2 shown by Fig. 1. When the improved lap-link is interposed between two terminal devices which it 90 connects, the draft or pulling-strain will be regularly exerted thereon and hold the elements 1 and 2 closed, so that it will be impossible for a disengagement therefrom of the said terminal devices. 95

It will be understood that changes in the

proportions, dimensions, and minor details may be resorted to without departing from the spirit of the invention.

Having thus fully described the invention, 5 what is claimed as new is—

A lap-link, consisting of two flat pivoted links of similar size and shape having slots cut through the side members thereof so that when the members are closed, the slots will

be in reverse positions, and inclined in opposite directions, the ends produced by the slots being connected by the pivot means.

In testimony whereof I affix my signature in presence of two witnesses.

ROBERT M. WAKEFIELD.
